DESIGN FOR A BATH MITT

Susan Clare Pearson, New York, N. Y.

Application July 26, 1938, Serial No. 78,736

Term of patent 14 years

To all whom it may concern:

Be it known that I, Susan Clare Pearson, residing in the Borough of Manhattan, city, county, and State of New York, have invented a new, original, and ornamental Design for a Bath Mitt, of which the following is a specification, reference being had to the accompanying drawing, forming part thereof.

In the drawing,

Figure 2 is a side view of Figure 1 showing that the back of the bath mitt is plain, the raised design being only on the palm side.

I claim:

The ornamental design for a bath mitt, as shown and described.

SUSAN CLARE PEARSON.
